US00D900808S

(12) **United States Design Patent** (10) **Patent No.:** **US D900,808 S**
(45) **Date of Patent:** **** Nov. 3, 2020**

(54) **BODY OF A SMART WATCH**

(71) Applicant: **Fitbit, Inc.**, San Francisco, CA (US)

(72) Inventors: **Gregoire Ludovic Vincent**
Vandenbussche, San Francisco, CA (US); **Jonah Avram Becker**, San Francisco, CA (US); **Irina Igorevna Kozlovskaya**, San Francisco, CA (US); **Cory William Worth**, Palo Alto, CA (US); **Chadwick John Harber**, San Francisco, CA (US); **Junyong Park**, San Francisco, CA (US)

(73) Assignee: **FITBIT, INC.**, San Francisco, CA (US)

(**) Term: **15 Years**

(21) Appl. No.: **29/702,946**

(22) Filed: **Aug. 22, 2019**

Related U.S. Application Data

(63) Continuation of application No. 29/669,190, filed on Nov. 6, 2018.

(51) **LOC (12) Cl.** **14-02**

(57) **CLAIM**

The ornamental design for a body of a smart watch, as shown and described.

DESCRIPTION

FIG. 1 is a top, right side isometric view of a body of a smart watch showing our new design.

FIG. 2 is a top plan view of FIG. 1.

FIG. 3 is a right side elevation view of FIG. 1.

FIG. 4 is a left side elevation view of FIG. 1.

FIG. 5 is a front side elevation view of FIG. 1

FIG. 6 is a back side elevation view of FIG. 1; and,

FIG. 7 is a bottom plan view of FIG. 1.

The features shown in broken lines in the drawing depict portions of the body of a smart watch that form no part of the claimed design

1 Claim, 5 Drawing Sheets
